GEAR SHIFT STICK

George H. Hurst, Jr., Jenkintown, and James F. Hobbins, Philadelphia, Pa., assignors to Hurst Performance, Inc., Warminster, Pa.

Filed Jan. 20, 1970, Ser. No. 21,005

Term of patent 7 years

Int. Cl. D12—16

U.S. Cl. D14—6

FIG. 1 is a side elevational view of the gear shift stick embodying our new design.

FIG. 2 is a front elevational view of the same.

FIG. 3 is a rear elevational view of the same.

FIG. 4 is a side elevational view of the opposite side of the lower portion of FIG. 1; the opposite side of the shift stick being identical with the side shown in FIG. 1.

FIG. 5 is a top plan view of the portion enclosed in bracket 5 in FIG. 1.

FIG. 6 is a view looking in the direction of line 6—6 on FIG. 1.

FIG. 7 is a sectional view looking in the direction of line 7—7 of FIG. 1.

FIG. 8 is a sectional view looking in the direction of line 8—8 on FIG. 1.

The gear shift stick design of this application is characterized by the appearance of outward tapering of the stick commencing at the upper end adjacent the threaded portion and extending to a point of maximum thickness just above the bend of the stick, and of inward tapering of the stick from such point to the bottom of the stick. The stick is also characterized by a rounded appearance from the upper end to the curve of the stick.

What we claim is:

The ornamental design for a gear shift stick, as shown and described.
